(73) Assignee: **Hewlett-Packard Development Company, L.P.**, Houston, TX (US)

(**) Term: **14 Years**

(21) Appl. No.: **29/191,716**

DESCRIPTION

(22) Filed: **Oct. 10, 2003**

The ornamental design for a border and special function keys for a keyboard or similar article, as shown and described.

(51) **LOC (8) Cl. 14-02**

(52) **U.S. Cl. D14/396**

(58) **Field of Classification Search** D14/391–396,
D14/398, 399, 455, 456, 247; D3/276; 341/22,
341/23; 200/5 A, 5 R, 6 A, 6 R; 178/17 A,
178/17 C; 235/145 A, 145 R; 345/160, 167,
345/168; 400/484–489, 492, 682

FIG. 1 is a perspective view of a border and special function keys for a keyboard showing the design.

See application file for complete search history.

FIG. 2 is a top plan view of the border and special function keys.

(56) **References Cited**

FIG. 3 is a front elevation view of the border and special function keys.

U.S. PATENT DOCUMENTS

FIG. 4 is a right side elevation view of the border and special function keys.
